SOUND REPRODUCING APPARATUS

Raymond E. Bowley, San Anselmo, Calif.

Application September 12, 1932
Serial No. 632,763

REISSUED

18 Claims. (Cl. 181—31)

This invention relates to improvements in sound reproducers of the types adapted for use with radio receiving sets, theatre projectors and other devices used in transmitting sound vibrations.

An object of my invention is to provide an improved sound reproducer which is particularly adapted to increase the frequency range of tones without distortion.

10 Another object of my invention is to provide an improved sound reproducer having a construction capable of accurately reproducing the higher frequencies, harmonics, partials and overtones originally produced by a source of sound vibrations.

Another object of my invention is to provide sound reproducing apparatus capable of reducing and absorbing excessive sound vibrations ordinarily accompanying an increase of volume, 20 thereby finally effecting the production of tones having true and undistorted qualities.

A further object of my invention is to provide a loud speaker having a large number of tubular vibratory members arranged in positions whereby sound vibrations may be simultaneously transmitted in different directions to and from areas located immediately surrounding and adjacent the loud speaker.

A still further object of my invention is to 30 provide an improved sound reproducing unit including a loud speaker and a plurality of tubular members arranged in different positions in front of and adjacent the cone of the loud speaker, the said tubes forming a plurality of individual 35 air chambers within and through which sound vibrations may be carried to and from different areas located adjacent the loud speaker, whereby a satisfactory blending of the tones may be satisfactorily accomplished.

40 Other objects more or less apparent and too numerous to relate in detail, will appear from the description of my invention which is to follow.

In the accompanying drawing:

45 Fig. 1 is a rear elevation of sound reproducing apparatus constructed in accordance with my invention;

Fig. 2 is a section taken on the line 2—2 of Fig. 1;

50 Fig. 3 is a vertical sectional view taken on the line 3—3 of Fig. 1; and

Fig. 4 is an enlarged front view of a portion of the apparatus, showing certain parts thereof broken away and other parts in section.

55 Referring to the drawing the numeral 1 design-

nates a radio or reproducer cabinet or casing having an opening in its front side for the passage of sound waves and a plurality of vertically disposed partitions 2 extending rearwardly from the said front side or baffle or sound board. 60 Suitably secured to the front side of the cabinet by screws 3 or other suitable means is a cone-shaped loud speaker 4 having the usual means 5 at its reduced end for producing sound vibrations.

Secured between the outwardly disposed peripheral flange 4' of the loud speaker cone and the front side of the cabinet by means of the screws 3, is an auxiliary ring shaped diaphragm, generally designated by the letter D. The diaphragm D is positioned around the opening in the front side of the cabinet with certain tubes thereof extending across the said opening. As shown in Fig. 4 the diaphragm D includes a front ring shaped support 6, constructed from paper, fiber or other suitable material. The support 6 is spaced from the front side of the cabinet by pads 7 through which the screws 3 extend. The pads serve to prevent the disfiguration of a plurality of short tubes 8 which are secured to and are distributed around the front surface of the ring shaped support 6 in spaced relation to one another. Positioned between the ring shaped support 6 and another similarly shaped and constructed support 9, are a plurality of vertically disposed tubular members 10, constructed from paper, fiber, or other suitable material. Positioned between the ring shaped support 9 and a rearwardly disposed support 11, having the same shape and construction, are a plurality of horizontally disposed tubular members 12, some of which extend entirely across the central openings in the ring shaped supports. Suitably secured to the rear surface of the support 11 are a plurality of short tubes 13 which are distributed around the said support in spaced relation to one another. A plurality of pads 14, interposed between the annular flange 4' of the cone 4 and the rearwardly disposed support 11 serve to prevent disfiguration of the tubes 13. The screws 3 extend through the pads 14 and 7 and serve as means for maintaining the auxiliary diaphragm and the cone 4 in their proper positions with reference to the opening in the front side of the cabinet.

The tubular members 10 and 12 are suitably affixed to the ring shaped supports by glue or other suitable means.

The tubular members 10 and 12, being disposed in opposite directions, connect areas in the cabinet located outside the cone 4 with the space

located directly in front of the said cone, thereby permitting sound vibrations to freely circulate between these areas. Some of the tubular members 12 extending entirely across the space in front of the open end of the cone and connect areas in the cabinet located on opposite sides of the loud speaker. The spaced short tubes 13 being circumferentially distributed around the ring shaped supports 6 and 11, serve to provide vibratory air chambers which communicate with different areas located around and between the supports.

Extending across the space in the cabinet located between the partitions 2 and either above or below the loud speaker cone 4, are a plurality of tubular members 15, which are preferably graduated as to size. The ends of the tubular members 15 extend entirely through the partitions 2 and serve to provide means for carrying sound vibrations from one side of the cabinet to the other.

The sound vibrations produced by the device 5, which in a radio receiving set is the means employed for translating electrical impulses into sound vibrations, proceed through the cone 4 and cause the same to vibrate in the usual manner. The sound vibrations produced within and around the cone 4 pass in various directions through the tubes and tubular members of the auxiliary diaphragm D, thereby causing a complete blending of the tones finally proceeding through the opening in the front of the cabinet. The tubular members and tubes provide a multiplicity of air chambers within which the sound vibrations proceed to and from different parts of the cabinet, and the vibration of said tubes thereby causes the production of high frequencies, harmonics and overtones, with the final result that accurately reproduced tones reach the ears of the listener. The larger tubes 15 located at the rear of the loud speaker cone 4 carry the sound vibrations from one side of the cabinet to the other, thereby materially assisting in the blending and intermingling of the sound vibrations within these areas. Those of the tubes 12 which extend across the openings in front of the cone 4 provide air chambers or passages which carry sound waves from one side of the loud speaker to the other. The large number of tubes associated with the loud speaker cause a multiplicity of vibrations to be simultaneously set up within the cabinet, thereby enriching the quality of the tones which finally proceed to the ear of the listener.

The various tubes and tubular members associated with the loud speaker may be constructed in any desired form or shape from any desirable kind of material, it being apparent that other forms may be employed with equal satisfaction. The particular arrangement and relative positions of the tubes may be also varied to meet certain conditions, it sometimes being desirable to employ a larger number of tubes with their relative positions being arranged in a different order than shown on the drawing. It is therefore desired that the limits my invention may assume be governed by the appended claims rather than by the particular form shown and described herein.

Having described my invention what I claim is:

1. Sound reproducing apparatus comprising a source of sound, a vibratory diaphragm associated with the source, and an auxiliary diaphragm including a plurality of tubular members mounted on supporting means, the auxiliary diaphragm

being in physical contact with the vibratory diaphragm.

2. In sound reproducing apparatus, a vibratory cone-shaped diaphragm, and a plurality of tubular members extending from points outside the diaphragm to points in front of the interior of the same, the said members being positioned substantially at right angles to the axis of the diaphragm.

3. In sound reproducing apparatus, a cone-shaped diaphragm having means for producing sound vibrations at its reduced end, an auxiliary diaphragm engaging the enlarged end of the cone-shaped diaphragm, the said auxiliary diaphragm including a plurality of tubular members mounted on a supporting member.

4. In sound reproducing apparatus, a cone-shaped diaphragm having sound reproducing means associated therewith, and a series of tubular members positioned across the enlarged end of the diaphragm at right angles to the axis thereof.

5. In sound reproducing apparatus, a cabinet, a loud speaker mounted in the cabinet, and an auxiliary diaphragm including a plurality of tubular members mounted on a ring shaped support, the said diaphragm being interposed between the loud speaker and the cabinet.

6. In sound reproducing apparatus, a cabinet having a sound opening therein, a loud speaker unit positioned to direct sound vibrations through the opening, and a series of hollow members interposed between the loud speaker and the cabinet, the said members being in contact with the loud speaker.

7. In sound reproducing apparatus a cabinet having a sound opening in its side, a cone-shaped loud speaker positioned with its enlarged end adjacent the opening in the cabinet, and a series of hollow members located between the front end of the loud speaker and the cabinet, certain of the hollow members being in contact with the loud speaker.

8. In sound reproducing apparatus, a cabinet having a sound opening therein, a loud speaker positioned directly behind the opening, and an auxiliary diaphragm positioned between the loud speaker and the cabinet and located at points around the said opening, the said auxiliary diaphragm including a plurality of sets of hollow members, the hollow members of one set being disposed at an angle to the hollow members of another set.

9. In sound reproducing apparatus, a cabinet having a sound opening therein, a partition member in the cabinet forming a plurality of compartments, sound reproducing means in the cabinet, and a plurality of tubular members located at the rear of the sound reproducing means extending from one compartment to another.

10. In sound reproducing apparatus, an auxiliary diaphragm comprising a support having a plurality of hollow members secured thereto.

11. In sound reproducing apparatus, an auxiliary diaphragm comprising a support having a plurality of tubular members secured thereto, some of the tubular members being positioned at angles to other of the said members.

12. In sound reproducing apparatus, a cabinet divided into one or more compartments, a loud speaker mounted in the cabinet, and a plurality of hollow members located at the rear of the loud speaker and extending from one compartment to another.

13. In sound reproducing apparatus, a cabinet having a sound opening in a side thereof, a cone-shaped diaphragm positioned in the cabinet with its enlarged end attached to the side of the cabinet at points around the opening therein, and an auxiliary diaphragm interposed between the cabinet and the enlarged end of the loud speaker, the said auxiliary diaphragm including a support having a plurality of hollow members secured thereto.

14. In sound reproducing apparatus, a cabinet having a sound opening therein, a source of sound vibrations, a cone-shaped diaphragm associated with the source of sound vibrations, the enlarged end of the cone-shaped diaphragm being attached to the cabinet at points adjacent the opening in the latter, and an auxiliary diaphragm interposed between the enlarged end of the cone-shaped diaphragm and the cabinet, the said auxiliary diaphragm including a plurality of spaced ring shaped supports having a series of tubular members secured thereto.

15. In sound reproducing apparatus, sound reproducing means having a diaphragm associated

therewith, and a plurality of tubular members engaging with the diaphragm.

16. In sound reproducing apparatus, a sound board having a sound opening therein, sound reproducing means positioned adjacent the sound board, and a plurality of tubular members interposed between the sound board and the sound reproducing means, certain of the tubular members being in contact with the sound board and certain of the tubular members being in contact with the sound reproducing means.

17. In sound reproducing apparatus, a sound board, a vibratory diaphragm positioned adjacent the sound board, and a plurality of tubular members interposed between the diaphragm and the sound board, the tubular members being disposed at approximately right angles to the axis of the diaphragm.

18. In sound reproducing apparatus, a source of sound, a vibratory diaphragm associated with the source of sound, the said diaphragm having a rim thereon, and a plurality of tubular members engaging the rim of the diaphragm.
